UNITED STATES PATENT OFFICE

EMIL M. BENSON, OF WORCESTER, MASSACHUSETTS, ASSIGNOR TO ROCKWOOD SPRINKLER COMPANY OF MASSACHUSETTS, OF WORCESTER, MASSACHUSETTS, A CORPORATION OF MASSACHUSETTS

DRY PIPE EXHAUSTER

Application filed April 13, 1931. Serial No. 529,598.

This invention relates to sprinkler systems in which the distributing pipes are normally filled with air under pressure, which air must be released before water can enter to supply an open sprinkler head.

If all of the air in the sprinkler system is forced out through the relatively small openings at one or two open sprinkler heads, a considerable period of time is required before water can reach the open sprinklers. In order to reduce this delay, exhaust devices have been provided, operable upon a predetermined drop in air pressure in the sprinkler system and venting the system rapidly when such a drop in pressure occurs.

It is the object of my invention to provide an improved construction of dry pipe exhauster in which a relay valve is utilized to open a main exhaust valve. A further object of the invention is to provide a construction by which the size of the dry pipe exhauster and the dimensions of the various parts thereof may be substantially reduced without reducing the exhausting capacity of the device as a whole.

My invention further relates to arrangements and combinations of parts which will be hereinafter described and more particularly pointed out in the appended claims.

A preferred form of the invention is shown in the drawings in which

Fig. 1 is a sectional side elevation of my improved dry pipe exhauster;

Fig. 2 is a plan view of the exhauster, partly in section;

Fig. 3 an end elevation thereof, partly in section; and

Fig. 4 is a view similar to Fig. 1 but showing the parts in a different position.

Referring to the drawings, my improved dry pipe exhauster comprises a casing C preferably formed of a body 10, a bottom member 11, and intermediate section 12, and a top member or cap 13. The bottom member 11 is secured to the body 10 by suitable clamping screws 15 and the top 13 and intermediate member 12 are secured to the body 10 by additional clamping screws 17 (Fig. 2 and 3). The body 10 is formed with three compartments or air chambers 20, 21, and 22, sep-

erated from each other by suitable partition members 23 and 24.

A pipe 25 (Fig. 1) connects the compartment 20 to the dry pipe sprinkler system above the usual dry pipe valve. The air chamber 20 is a pressure chamber, the chamber 21 a relay chamber and the chamber 22 an exhaust chamber. A vent pipe 27 connects the compartment or chamber 22 to the atmosphere, and a pipe 28 (Fig. 3) connects the compartment or chamber 21 to the intermediate chamber of the usual dry pipe valve (not shown), this chamber 21 being filled with air at atmospheric pressure under normal conditions.

An additional compartment or chamber 30 is formed in the intermediate casing member 12 and a relatively large air storage chamber 32 is formed in the top or cap 13. A suitable pressure gauge 33 may be connected through a pipe 34 to the storage chamber 32 to indicate the pressure therein, which is normally equal to the air pressure in the dry pipe system.

An opening 36 is formed in a partition 37 which separates the chambers 30 and 32 and a diaphragm 40 is clamped against the upper edge of the intermediate casing member 12 and underlies the opening 36.

A restricted bleed opening 42 is formed in a cross partition of a bushing 43, extending through the middle portion of the diaphragm 40 and secured thereto by a flanged clamping nut 44. Screens 46 are secured above and below the bleed opening 42 by caps or bushings 47 having air passages 48 formed therein.

With this construction, it will be evident that air can pass slowly back and forth between the chambers 30 and 32, tending to equalize the pressures therein.

A large exhaust port 50 is formed in the partition member 23 which separates the casing chambers 20 and 22. An exhaust valve 52 is mounted below the opening 50 and is pushed upward against a seating ring 53 by a coil spring 54.

The valve 52 is preferably provided with a disc 56 of leather or other suitable packing material, which engages the seating ring 53 around its periphery and also engages the

lower end of a sleeve or bushing 58, threaded into an opening 59 in the partition member 24 which separates the chambers 21 and 22. The bushing 58 not only provides an inner 5 annular seat for the valve but also constitutes a guide for the valve stem 60 extending upwardly from the valve 52.

A diaphragm 62 is clamped between the casing parts 10 and 12 and forms the upper 10 wall of the chamber 21. A disc 63 is secured in the center of the under side of the diaphragm 62, in position to engage the valve stem 60 when the diaphragm 62 is depressed. A small bushing 65 is mounted in the dia- 15 phragm 62, with a restricted bleed opening 66 extending therethrough.

A bushing 70 is secured in an opening in the partition 71 which forms the bottom of the air chamber 30. The upper end of the 20 bushing 70 forms a seat for a relay valve 72 having a loosely fitting valve stem 73 extending downward through the opening in the bushing.

The valve 72 is engaged by a valve lever 75, 25 mounted on a fixed pivot 76 and having an end portion 77 positioned for engagement by the lower end of the cap or bushing 47 carried by the diaphragm 40. A spring 78 holds the valve 72 normally seated.

Having described the construction of my 30 improved dry pipe exhauster, the use and operation thereof is as follows:

When the sprinkler system is filled with air under pressure, the air will flow through the 35 pipe 25 to the pressure chamber 20, raising the pressure therein and applying the increased pressure to the underside of the exhaust valve 52 to more firmly seat the valve against the seating ring 53 and the end of the bushing 58. The exhaust chamber 22 is at 40 all times at atmospheric pressure.

Air from the pressure chamber 20 also flows freely through a connecting passage 45 80 to the intermediate air chamber 30, raising the pressure therein and also gradually raising the pressure in the storage chamber 32 by seepage of air through the bleed opening 42. After a sufficient interval, the air chambers 20, 30, and 32 will all contain air at substantially the same pressure as that maintained 50 in the dry pipe system.

At this time, the relay chamber 21 is connected to the atmosphere through the pipe 28, which extends to the intermediate chamber 55 of the dry pipe valve. Furthermore, the air in the relay space 82 above the diaphragm 62 will also be at atmospheric pressure, by reason of the bleed opening 66 through the diaphragm 62.

The valve 72 is maintained in closed position by its own weight, also by the force of the spring 78, and furthermore by the excess in pressure in the intermediate chamber 30 above the atmospheric pressure in the space

Assuming now that one or more sprinkler heads open, the air pressure in the sprinkler system will be to fall, with a corresponding drop in pressure in the air pressure chamber 20, and in the intermediate chamber 30 70 freely connected therewith.

A higher pressure is maintained, however, in the storage air chamber 32 for a considerable period, due to the very slow rate at which air can escape from the chamber 32 through 75 the bleed opening 42. Consequently there is an excess in pressure above the diaphragm 40, which is thereby depressed, raising the valve 72 and allowing air from the chamber 30 to flow into the relay space 82 above the 80 diaphragm 62.

While the pressure in the intermediate chamber 30 has been somewhat reduced by the opening of the sprinkler heads, it is still very substantially above the atmospheric 85 pressure of the chamber 21, and consequently when the valve 72 is opened, the diaphragm 62 is pushed downward with sufficient pressure to depress the exhaust valve 52 and open the large exhaust passage 50 between the pressure chamber 20 and the exhaust chamber 22. 90

Thereupon, air will rush quickly through the opening 50 to the exhaust, very rapidly reducing the air pressure in the sprinkler system and allowing the air to escape therefrom, so that water may enter and be distributed to the open sprinklers. 95

As soon as the dry pipe valve opens and water is admitted to the sprinkler system, 100 water is conveyed to the lower part of the relay chamber 21 through the pipe 28, thus producing a pressure equal or in excess of the pressure in the space 82.

As soon as these pressures are equalized, 105 the spring 54 moves the exhaust valve 52 upward, closing the exhaust opening 50 and preventing escape of water through the exhaust pipe 27. The seating of the packing member 56 against the ring 53 forms a tight joint and prevents the escape of water from the pressure chamber 20, and the seating of the packing disc against the lower end of the bushing 58 forms a second tight joint which prevents escape of water from the relay chamber 21. 110 Consequently all objectionable leakage or dripping from the exhaust pipe 27 is avoided. 115

Having described the operation of my improved exhauster, it will be evident that the use of the relay valve 72 permits a substantial reduction in the diameter of the diaphragm 62. 120

In exhausters previously used, the large exhaust valve 52 was operated directly by the upper diaphragm 40, so that the force available for opening the exhaust valve was merely the difference in pressure between the sprinkler system and the air storage chamber 32. This difference being relatively small, the diaphragm 40 was necessarily of large diam- 125 130

eter in order to develop enough force to overcome the pressure on the exhaust valve 52.

In my improved construction, however, the force available for opening the exhaust valve 52 is the difference between the slightly reduced pressure in the intermediate chamber 30 and atmospheric. This difference in pressure is many times greater than the difference in pressure previously available, and consequently the diameter of the diaphragm 62 may be proportionately reduced, with a corresponding reduction in the size of the casing C and in the size of many of the associated parts.

15 The necessary difference in pressure between the air storage chamber 32 and the intermediate chamber 30 to open the relay valve 72 is comparatively small and may be adjusted by varying the tension of the spring 78. The spring is usually adjusted so that a difference of two or three pounds in pressure between the air chambers 32 and 30 will cause the relay valve 72 to be opened. The 20 sensitiveness of the device may also be increased by decreasing the size of the port opening for the relay valve 72, or by changing the ratio of the arms of the valve lever 75.

It should be noted that the relay valve 72 is normally closed not only by the pressure of the spring 78 but also by its own weight and by the substantial pressure of the air in the chamber 30.

Having described the details of construction of my improved air exhauster, it will be seen that the device is simple and reliable, containing few moving parts, and that substantial pressure is available for opening the exhaust valve 52 on a relatively small but 40 rapid drop in sprinkler system pressure.

Having thus described my invention and the advantages thereof, I do not wish to be limited to the details herein disclosed, otherwise than as set forth in the claims, but what 45 I claim is:—

1. An air exhauster comprising a pressure chamber continuously open to the sprinkler system, a vented exhaust chamber, a partition separating said chambers and having a relatively large exhaust port opening therethrough, an exhaust valve normally closing said opening, a spring assisting to close said exhaust valve, a relay chamber having a diaphragm mounted therein which separates said chamber into two parts continuously connected through a bleed opening, both parts of said relay chamber being normally at atmospheric pressure, a connection from said diaphragm to said exhaust valve, an intermediate air chamber in free communication with said pressure chamber, a normally closed relay valve between said intermediate chamber and one part of said relay chamber and opening toward said intermediate chamber, and means to open said relay valve upon a

predetermined abrupt drop in air pressure in said sprinkler system, thereby depressing said diaphragm and opening said exhaust valve.

2. The combination in an air exhauster as set forth in claim 1, in which said latter means 70 comprises an air storage chamber separated from said intermediate chamber by a diaphragm and continuously connected thereto through a second bleed opening.

3. The combination in an air exhauster as 75 set forth in claim 1, in which said latter means comprises an air storage chamber separated from said intermediate chamber by a diaphragm and continuously connected thereto through a second bleed opening, a lever connected to said relay valve, and a device on said diaphragm engaging said lever and effective to open said valve when said diaphragm is displaced toward said intermediate chamber.

4. The combination in an air exhauster as 80 set forth in claim 1, in which said latter means comprises an air storage chamber separated from said intermediate chamber by a diaphragm and continuously connected thereto through a second bleed opening, and a spring for supplementing the excess of air pressure above atmospheric in said intermediate chamber in holding said relay valve closed.

5. The combination in an air exhauster as 85 set forth in claim 1, in which said latter means comprises an air storage chamber separated from said intermediate chamber by a diaphragm and continuously connected thereto through a second bleed opening, and a spring 90 for supplementing the excess of air pressure above atmospheric in said intermediate chamber in holding said relay valve closed, said spring being adjustable to vary the pressure differential between said storage chamber and said intermediate chamber required for opening said relay valve.

6. The combination in an air exhauster as set forth in claim 1, in which said latter means comprises an air storage chamber separated 100 from said intermediate chamber by a diaphragm and continuously connected thereto through a second bleed opening, and said bleed opening being formed in the central disc of a bushing mounted in an opening in 105 said latter diaphragm.

7. The combination in an air exhauster as set forth in claim 1, in which the pressure chamber has an inlet opening and the exhaust chamber has an outlet opening, and in which 120 said two openings are substantially in horizontal and axial alignment.

8. An air exhauster comprising a pressure chamber continuously open to the sprinkler system, a vented exhaust chamber, a partition 125 separating said chambers and having a relatively large exhaust port opening therethrough, an exhaust valve normally closing said opening, a spring assisting to close said exhaust valve, a relay chamber having a dia- 130

phragm mounted therein which separates said chamber into two parts continuously connected through a bleed opening, both parts of said relay chamber being normally at atmospheric pressure, a valve rod for said exhaust valve extending into said relay chamber, means to introduce air under pressure to one part of said relay chamber and thereby cause said diaphragm to act through said valve rod to open said exhaust valve, and a bushing for said valve rod, said partition and said bushing having annular seats each directly engaged by said exhaust valve.

10 In testimony whereof I have hereunto affixed my signature.
